United States Patent Office

Des. 207,960
Patented June 20, 1967

207,960

GAME BOARD

Calvin L. Payne, Jr., Hastings on Hudson, N.Y., assignor
to Tudor Metal Products Corporation, Brooklyn, N.Y.,
a corporation of New York

Filed July 27, 1965, Ser. No. 86,301

Term of patent 14 years

(Cl. D34—5)

FIGURE 1 is a perspective view of a game board showing my new design.

FIGURE 2 is a side view of the game board; and

FIGURE 3 is a front view showing the game board in elevation.

The dominant features of my design reside in the portions shown in full lines.

I claim:

The ornamental design for a game board, as shown and described.
